HYDRAULIC SPEED CONTROL APPARATUS

Warren R. Tucker, Dayton, Ohio, assignor to
H-P-M Development Corporation, Wilmington,
Del., a corporation of Delaware

Application February 23, 1944, Serial No. 523,505

9 Claims. (Cl. 60—97)

1

This invention relates to control systems and, in particular, to hydraulic control systems. This invention has to do, in particular, with the simultaneous control of two or more moving elements such as rotary or translating members.

There are many classes of work in which it is desired to more or less accurately synchronize the operation of individual elements. For example, on machines for winding continuous materials such as thread or paper it is necessary to have a number of rollers all of which rotate at the same speed. Thus, a constant tension is exerted on the material being wound and a properly uniform product results. It will be obvious that any great difference in speed between a pair of rollers carrying the same thread will result in the breakage of the strand.

Other examples of arts requiring coordination between the various machine elements include paper making machines, glass making machines and various other types of rolling or winding operations.

One method of driving these various elements, and at the same time attempting to synchronize the same, has been to provide separate hydraulic motor drives for each element and to direct the exhaust fluid from one motor to the inlet of the next. This method of synchronizing several different elements has proved to be unsatisfactory since each of the driving motors must be identical with every other as regard displacement and leakage of pressure fluid therethrough. Furthermore, in a series arrangement such as this, the errors outlined above are cumulative and the discrepancy between the actual position of the driven element and the desired position becomes greater as the operation continues.

Accordingly, it is the primary object of the present invention to provide a control system for a plurality of driven elements whereby the same may be substantially synchronized.

It is a further object to provide an improved hydraulic control system for accomplishing the above.

It is another object of this invention to provide a hydraulic control system for synchronizing the operation of several different driven elements, while providing individual controls for adjusting the speed of each element independently of the others.

These and other objects will be apparent upon reference to the following detailed description and attached drawing, in which:

Figure 1 is a view of a hydraulic circuit which, for the most part, is presented diagrammatical-

2

ly for the purpose of better illustrating this invention, and

Figure 2 is a perspective view of the throttle valve member by which the simultaneous control of a plurality of motors is obtained; and

Figure 3 is a cross-section taken on the line 3—3 of Figure 1, showing the throttling unit forming a part of this system.

General arrangement

10

The general arrangement of this invention, as shown in Figure 1, comprises a plurality of hydraulic motors and a plurality of pumps for supplying actuating fluid thereto. The plurality of 15 motors provide the driving power for an equal number of machine elements, such as rollers, the operation of which it is desired to synchronize.

For the purpose of synchronizing the operation of the motors and, therefore, the elements driven 20 thereby, a unitary control member is provided. This control means, according to the preferred embodiment of this invention, comprises means for varying the displacement of the pumps in order to maintain the speeds of the motors driven 25 thereby at any predetermined value.

While the preferred embodiment of my invention comprises constant displacement motors driven by variable displacement pumps, it is possible to invert this arrangement and provide variable displacement motors and constant displacement pumps.

Detailed description

Referring to Figure 1, there is provided a plurality of driven members such as hydraulic motors indicated at 5, 6 and 7. These motors are of the constant displacement type, but as will be explained later, may be replaced by variable displacement motors.

40 Pressure fluid is supplied to the motors 5, 6 and 7 by means of conduits 8, 9 and 10 respectively, which in turn are connected to the outlets of the pumps 11, 12 and 13, respectively. The pumps 11, 12 and 13 draw fluid from a reservoir 14 through the conduits 15, 16 and 17, respectively. The pumps 11, 12 and 13 are preferably of the variable displacement type but may, as will become hereinafter apparent, be replaced by constant delivery or constant displacement pumps 45 without departing from the spirit of this invention.

The exhaust from the motors 5, 6 and 7 is conducted by means of the conduits 18, 19 and 20, respectively, to a control unit generally indicated 50 at 21.

The control unit 21 is freely exhausted by means of a conduit 22 to the reservoir or any other suitable fluid collecting means. The control unit 21 comprises a casing 23 having an axial bore 24 therein. The conduits 18, 19 and 20 communicate with the bore 24 and the bore 24, in turn, is exhausted by means of the conduit 22.

Inserted within the bore 24 is a member 25 which is provided with notches 26 which are adapted to be positioned between the inlet and outlet conduits of the control unit 21. The member 25 terminates, at the one end, in a square shank or other suitable means for adjusting the angular position thereof as indicated at 27. The portion 27 extends externally of the casing 23, to the left as shown in Figure 1, and a suitable locking means such as the knurled hand wheel 28 provides a means for locking the member 25 in any particular position of adjustment.

As will be seen from Figure 3, the notches 26 in the member 25 provide a means for creating a restriction between the inlet conduit and the exhaust conduit. This restriction may be varied by adjusting the angular position of the member 25. It will be apparent that the restriction offered to the flow of fluid from each of the conduits 18, 19 and 20 is varied simultaneously and identically as the member 25 is adjusted.

Referring now to the variable displacement pump units, and particularly to the pump 11, this will be seen to comprise a shiftable flow controlling member 28 having an adjustable yielding means such as the spring 29 continuously urging the same toward full delivery position. The spring 29 is adjusted by means of the threaded rod 30 and the hand wheel 31.

Opposing the thrust of the spring 29 is a plunger 32 to which is attached a piston 33, the latter being reciprocable within a cylinder 34. The establishment of a predetermined pressure within the right hand end of cylinder 34 is effective to cause the piston 33 through the plunger 32 to move the flow controlling member 28 to the left against the thrust of the spring 29 thereby to reduce the delivery of the pump associated therewith.

The pressure for actuating the piston 33 is supplied to the cylinder 34 by means of a conduit 35 which is connected with the exhaust conduit 18.

Inasmuch as the pumps 12 and 13 are identical in construction with the pump 11 the similar parts are identified by the same numbers as are the parts of the pump 11.

Operation

In operation, the pumps 11, 12 and 13 are driven in any suitable manner from a single power source or from individual power sources. The pumps deliver through the conduits 8, 9 and 10 to the motors 5, 6 and 7, respectively, the motors being provided with output shafts 36, 37 and 38, respectively for driving rolls or other suitable machine elements.

The exhausts from the motors are conducted to the control unit 21 where each is throttled an identical amount in passing therethrough to the exhaust conduit 22.

The restrictions within the control unit 21, created by the notches 26, is effective to maintain a predetermined pressure in each of the conduits 18, 19 and 20, which pressures are conducted through the conduits 35 to the control cylinders 34 to act upon the pistons 33.

The effect of the pressure conducted to each

cylinder 34 through the conduit 35 associated therewith is to move the shiftable flow control member of the associated pump toward neutral against the thrust of the spring 29. The pump will move toward neutral, reducing its delivery and, therefore, the exhaust from the motor, until the pressure created at the motor exhaust by the control unit is reduced to such a point that the thrusts of the spring and the piston 33 are exactly balanced. This action takes place in each of the three pump-motor units and the three motors will, when the thrusts of the three springs 29 are properly adjusted, be running with equal speeds.

The effect of the restrictions in the motor exhaust conduits is to maintain this speed constant, inasmuch as a reduction thereof will permit the spring 29 to increase the delivery of the pump, and an increase thereof will cause the piston 33 to move to reduce the delivery of the pump.

In case it is desired to operate one or more of the motors at a different speed from the others, this may be accomplished by adjusting the spring 29 by means of the threaded rod 30 and hand wheel 31. As the thrust of the spring is increased the motor associated with that pump will operate at a greater speed than the others and vice-versa as the thrust of the spring is decreased. The manual adjusting means for adjusting the thrust of the spring of each pump is likewise useful for making minor adjustments such as might occur on account of leakage of hydraulic fluid or from slight dissimilarities in the displacements of the various pumps and motors.

It will be apparent that, once the speed ratios of the various motors relative to one another have been adjusted by means of the springs 29, the adjustment of the central control means 21 will be effective to cause proportional changes in the speeds of all the motors simultaneously and without changing the aforementioned speed ratios.

It will also be apparent that this invention is not limited to the control of three motors, as shown, but may be extended to control as many motors as it is desired. It will also be apparent that either the motor or the pump or both could be variable displacement units without in any way departing from the spirit of this invention.

Accordingly, it will be understood that I do not wish to be limited by the specific structures and arrangements shown in the drawings, but desire to comprehend such modifications as come within the scope of the appended claims.

Having thus fully described my invention, what I claim as new and desire to secure by Letters Patent is:

1. In a hydraulic system; a plurality of fixed displacement fluid operable motors having fluid inlets and fluid outlets; a movable work member associated with each of said motors to be driven thereby; a plurality of variable delivery pumps respectively hydraulically connected with said motor inlets and having movable flow control members; a plurality of choke valves having their inlets respectively hydraulically connected with said motor outlets, the outlets of said chokes being connected to exhaust; a member common to all of said choke valves and movable to adjust the throttling effects thereof simultaneously and equally; a plurality of fluid operable plungers respectively hydraulically connected to the in-

lets of said chokes, said plungers also being respectively connected with the flow control members of said variable delivery pumps; a plurality of yielding means continuously urging said flow control members toward increased delivery position; and means for adjusting the thrust of each of said yielding means whereby the pressures created at the inlets of said chokes by the flow of fluid through said motors will urge said flow control members toward reduced delivery position with a thrust equal to that of said yielding means, the thrust of the latter being in accordance with the individual adjustment thereof.

2. In a hydraulic system; a plurality of fixed displacement fluid operable motors having fluid inlets and fluid outlets; a movable work member associated with each of said motors to be driven thereby; a plurality of variable delivery pumps respectively hydraulically connected with said motor inlets and having movable flow-control members; a plurality of choke valves having their inlets respectively hydraulically connected with said motor outlets, the outlets of said chokes being connected to exhaust; a member common to all of said choke valves and movable to adjust the throttling effects thereof simultaneously and equally; a plurality of fluid operable plungers respectively hydraulically connected to the inlets of said chokes, said plungers also being respectively connected with the flow control members of said variable delivery pumps; a plurality of yielding means continuously urging said flow control members toward increased delivery position; whereby the pressures created at the inlets of said chokes by the flow of fluid through said motors will urge said flow control members toward reduced delivery position with a thrust equal to that of said yielding means, the thrust of the latter being in accordance with the individual adjustment thereof.

3. In a hydraulic system; a plurality of fluid operable motors having fluid inlets and fluid outlets; a movable work member associated with each of said motors to be driven thereby; a plurality of pumps respectively hydraulically connected with said motor inlets; a plurality of throttle valves having their inlets respectively hydraulically connected with said motor outlets and their outlets connected to exhaust; a means associated with all of said throttle valves and selectively operable to adjust the throttling effects thereof simultaneously and equally; a plurality of fluid operable means respectively hydraulically connected to the inlets of said throttle valves and operable, in response to variations in pressure at the inlets of said chokes, to vary the relative displacements of said pumps and said motors, thereby to maintain the speeds of said motors and, therefore, the speed of said work members substantially constant.

4. In a hydraulic system; a plurality of fluid operable motors having fluid inlets and fluid outlets; a movable work member associated with each of said motors to be driven thereby; a plurality of pumps respectively hydraulically connected with said motor inlets; a plurality of throttle valves having their inlets respectively hydraulically connected with said motor outlets and their outlets connected to exhaust; a means associated with all of said throttle valves and selectively operable to adjust the throttling effects thereof simultaneously and equally; a plurality of fluid operable means respectively hydraulically connected to the inlets of said throttle valves and operable, in response to varia-

tions in pressure at the inlets of said chokes to vary the displacements of said pumps relative to said motors and inversely to said pressure variations, thereby to maintain the speeds of said motors and, therefore, the speed of said work members substantially constant.

5. In a hydraulic system; a plurality of fluid operable motors having fluid inlets and fluid outlets; a work shaft associated with each of said motors to be driven thereby; a plurality of variable delivery pumps respectively hydraulically connected with said motor inlets; a plurality of throttle valves having their inlets respectively hydraulically connected with said motor outlets; means for adjusting the throttling effects of all of said throttle valves simultaneously; a plurality of fluid operable servomotors respectively hydraulically connected to the inlets of said throttle valves and associated with said variable delivery pumps and adapted, in response to variations in pressure at the inlets of said throttle valves, to actuate said servomotors to vary the rates of delivery of said pumps thereby to maintain the speeds of said motors substantially constant.

6. In a hydraulic system; a plurality of fluid operable motors having fluid inlets and fluid outlets; a work shaft associated with each of said motors to be driven thereby; a plurality of variable delivery pumps respectively hydraulically connected with said motor inlets; a plurality of throttle valves having their inlets respectively hydraulically connected with said motor outlets; means for adjusting the throttling effects of all of said throttle valves simultaneously; a plurality of fluid operable servomotors respectively hydraulically connected to the inlets of said throttle valves and associated with said variable delivery pumps and adapted, in response to variations in pressure at the inlets of said throttle valves, to actuate said servomotors to vary the rates of delivery of said pumps inversely to said pressure variations, thereby to maintain the speeds of said motors substantially constant.

7. In a system for selecting and controlling the speeds of a plurality of fluid operable motors having fluid inlets and fluid outlets; a fluid operable control means associated with each of said motors and operable, in response to a predetermined fluid pressure, to vary the supply of actuating fluid to said motor; a flow responsive means associated with the outlet of said motor and operable to maintain a predetermined pressure at said motor outlet; conduit means hydraulically connecting said motor outlet with said fluid operable control means; means for adjusting each of said fluid operable control means independently of the others; and means selectively operable for adjusting all of said flow responsive means simultaneously and equally.

8. In a hydraulic system; a plurality of fluid operable motors; a source of pressure fluid for supplying actuating fluid to said motors; a plurality of flow responsive means respectively associated with said motors and arranged serially therewith and operable to create pressures proportional to the speeds of said motors; a member common to all of said flow responsive means and movable to adjust all of said means simultaneously; a plurality of fluid operable flow controlling means respectively hydraulically connected with said flow responsive means and associated respectively with said motors and operable to vary the supply of fluid to said motors in inverse proportion to the pressure applied to

said flow control means; and means for varying the response of each of said flow controlling means independently, whereby adjustment of said last mentioned means is effective to adjust the speed of the associated motor independently of the others and adjustment of said flow responsive means is effective to adjust the speeds of all of said motors simultaneously and in proportion.

9. In a system for selecting and controlling the speeds of a plurality of fluid operable motors; a fluid pressure responsive control means associated with each of said motors; a flow responsive means serially connected with each of said motors and operable to create a pressure difference between its inlet and its outlet in proportion to the rate of fluid flow therethrough; means conveying the pressure difference generated by each of said flow responsive means to the control means associated with the same motor; means 20 for adjusting each of said control means independently of the others and means selectively

operable for adjusting all of said flow responsive means simultaneously and equally.
